CLAIM

The ornamental design for a zippered headphone, as shown and described.

DESCRIPTION

This application claims priority to application Ser. No. 29/416,055, and application Ser. No. 29/416,058, the contents of which are incorporated by reference herein in their entireties.

FIG. 1 is a front perspective view of zippered headphone showing our new design, the opposite perspective view is a mirror image, the cord is drawn broken away for indeterminate length;

FIG. 2 is a front view thereof;

FIG. 3 is a back side view thereof;

FIG. 4 is a side view thereof;

FIG. 5 is a top view thereof; and,

FIG. 6 is a bottom view thereof.

1 Claim, 6 Drawing Sheets
